UNITED STATES PATENT OFFICE.

WALTER C. SCHNEIDER, OF ADAMS, WISCONSIN.

ELECTRICAL SPARKING DEVICE.

Application filed January 7, 1922. Serial No. 527,642.

To all whom it may concern:

Be it known that I, WALTER C. SCHNEIDER, a citizen of the United States, residing at Adams, in the county of Adams 5 and State of Wisconsin, have invented certain new and useful Improvements in Electrical Sparking Devices, of which the following is a specification.

The invention relates to certain improvements in electrical sparking devices generally, and more particularly to a spark plug type thereof adapted for use in igniting fuel charges in the cylinders of internal combustion engines and the like.

15 The principal object of the invention is to provide for a means cooperative with the opposed end portions or surfaces of the electrodes forming a spark gap, whereby to eliminate any and all tendency to the carbonizing of the active portions of the said electrodes, throughout continued use thereof, such as otherwise greatly lessens or 20 completely destroys the effectiveness of the said spark gap.

25 Another object of the invention is to provide for a sparking device of the class mentioned, and one involving the use of a metal element between the opposed ends or active surfaces of the electrodes forming the spark 30 gap of the device, whereby the same forms a part of the electrical circuit thereof, and which is operable under the impulses of successive explosions of fuel charges within the cylinders of an engine for preventing 35 the accumulations of carbon and oil on the active ends or surfaces of said electrodes.

40 A further object of the invention is to provide for a means as characterized, and one capable of being applied to spark plugs of standard types without any serious modification or change in the general features of construction and arrangement of the parts thereof.

45 With the foregoing and other objects in view, the invention resides in the certain new and useful construction and arrangement as will be hereinafter more fully described, set forth in the appended claims, and illustrated in the accompanying drawing, in which:

Figure 1 is a vertical section taken on the line 1—1 of Figure 2, and shows a preferred embodiment of the improved spark plug,

50 Figure 2 is a bottom plan view thereof, and;

Figure 3 is an elevation of the same, partly in section.

Referring to the drawing, the numeral 6 indicates the metal body or shell of a spark plug having a reduced and exteriorly 60 threaded lower extension 6 adapted for engagement in a complementally threaded spark plug opening of the cylinder of an internal combustion engine (not shown). This reduced extension 6 is provided with a 65 concentrically disposed bore 7, which opens into a bore 8 of a larger diameter and similarly formed in the upper portion of the body or shell 5. Seated within the body or shell 5 is a body or core 9 of an insulating 70 material, which is formed to provide a lower tapered end portion 10 depending downwardly through the bore 7 and having its lower end projecting for a slight distance below the lower end of the reduced 75 end portion 6 of the plug or shell 5, and an annular shouldered portion 11 at the upper end of the tapered portion 10 snugly fitting the larger bore 8 in the upper end portion of the plug or shell 5. This insulating body 80 or core 9 is rigidly secured in position, by means of a clamp nut 12, which is passed downwardly over the upper end of the same and is threaded into the upper end of the bore 8 of the plug or shell 5 for the purpose. To prevent any loss of compression from the cylinder of the engine, with which the spark plug is being used, and upwardly of the bores 7 and 8 of the plug or shell 5, packing gaskets or washers 13 and 14 are 85 interposed between the lower end wall of the bore 8 and the inner end of the clamp or jam nut 12 and the lower and upper shoulders of the enlarged annular portion 90 11, of the insulating body or core 9, opposed thereto, substantially as shown.

95 The insulated body or core 9 is formed with a concentrically disposed and longitudinally extending bore 15, which is counter sunk at its lower end to provide an inwardly 100 tapered portion 16, and has inserted upwardly therethrough a center electrode 17. Inwardly of the lower end of the electrode 17, the same is provided with an annular portion or collar 18, which abuts the shouldered wall portion at the inner end of the tapered bore 16 and determines the length 105 of the lower end portion of the electrode depending from the bore 15 and within the confines of the latter. With the portion or 110

collar 18 so arranged, the upper end of the electrode 17 projects for a distance above the upper end of the insulating body or core 9 and has positioned thereon, in the order named, a metal washer 19, a securing nut 20, and an ignition circuit lead binding nut 21.

Extending diametrically across the lower end of the body or shell 5, and spaced therefrom is a bar or strap form of electrode 22, which has its opposite ends angularly bent for connection with the wall of the lower reduced portion 6, whereby the same is electrically grounded through the body or shell 5 to the engine. The medial portion of the electrode 22 also extends diametrically across the lower end of the insulated body or core 9, and consequently and correspondingly so across the tapered bore 16 therein and has its inner face opposed by the lower end of the center electrode 17, which is spaced for a distance inwardly of the said bore 16. Loosely mounted within the open end of the tapered bore 16, of the insulated body or core 9 and between the lower end of the center electrode 17 and the inner face of the electrode 22, is a metal member 23, preferably in the form of a spherical body or ball, which, when resting on the latter, provides for a spark gap between its upper surface and the opposed end of the central electrode 17 and of the usual length, or of about three sixty-fourths of an inch. To assure of the positive ignition of a fuel charge by a spark passing between the lower end of the center electrode 17 and the upper surface of the spherical body or ball 23, the wall of the lower end of the insulated body or core 9 is provided with a series of equidistantly spaced recesses 24, which are outwardly flared as at 25, and these recesses 24 open directly into the tapered bore thereof in line with the spark gap between the electrodes for such purpose.

In the use of spark plugs constructed and arranged in accordance with the invention, and when the same are positioned in the walls of the cylinder or cylinders of an internal combustion engine in the ordinary manner of mounting thereof and properly connected in on the ignition circuit, the spherical body or ball 23 will rest on the upper or inner face of the grounded electrode 22, so that a spark gap is provided as hereinbefore explained. Upon the completion of the ignition circuit, through the center electrode 17, a spark will be created at the lower end of the latter and will jump the gap to the upper surface of the body or ball 23, and ignite the fuel charge through the recesses 24 and the open end of the tapered bore 16. During successive explosions of fuel charges within the cylinder or cylinders of the engine, the movable bore or vertical member 23, constituting within

itself a freely movable electrode ordinarily grounded to the bar electrode 22 and the plug or shell 5 of the spark plug, is continually jostled or impacted against the active sparking surfaces or ends of both of the stationary electrodes 17 and 22, and in a manner to always, or nearly so, present a fresh portion of its own surface to the center electrode 17, also, by reason of the force of such jostling or impact, under the force of the successive explosions of the fuel charges, the active surfaces of all of the metal parts forming the spark gap will be kept free from accumulations or deposits of carbon and oil, such as otherwise greatly lessens or completely destroys the effectiveness of the spark plug. In practice, it has been found that the action of the movable electrode 23, and the force of the impact imparted to the same, is sufficient to effectually prevent the depositing of carbon and oil on the electrodes, and to such an extent as to greatly increase the length of life of the spark plug, and to maintain the same at a high standard of efficiency, such as is not obtainable in the use of present and known constructions of spark plugs.

From the foregoing, it will be readily apparent that, while a preferred embodiment of the spark plug has been described and illustrated herein in specific terms and details of construction and arrangement, various changes in and modifications of the same may be resorted to without departing from the spirit of the invention, or the scope of the claims appended hereto.

Having thus fully described the invention, what is claimed, is:

1. A spark plug for internal combustion engines comprising a metallic shell, a core of insulation mounted therein, an electrode disposed concentrically of said core and having its inner end positioned above the inner end of the latter, an electrode formed integral with and extending across the inner end of the shell and further spaced below the inner end of the core, and a freely movable globular metallic element extended within the inner end of the core, and interposed between the opposed portions of said electrodes and operable under the force of the explosions in an engine cylinder to prevent accumulation of carbon and oil on the oppositely acting sparking surfaces of said electrode, and said core having its inner end provided with a plurality of equidistantly spaced outwardly flared recesses opening through the core in line with the spark gap between the electrodes.

2. In a spark plug for internal combustion engines, a metallic shell, a core of insulation extending therethrough, an electrode disposed concentrically of said core and having its inner end positioned inwardly with respect to the inner end of the core, a transversely extending U-shaped electrode having

its end integral with said shell at diametrically opposite points and extending across and positioned in close proximity to the inner end of said core, and a freely movable globular metallic element supported by said U-shaped electrode and extended in the inner end of the core and further interposed between the opposed portions of said electrode,

and said core having the inner end thereof provided with a plurality of equidistantly spaced outwardly flared recesses opening through the core in line with the spark gap between said electrodes. 10

In testimony whereof, I affix my signature hereto.

WALTER C. SCHNEIDER.
